ARCHIE MACPHAIL NIVEN, OF DETROIT, MICHIGAN, ASSIGNOR TO CONTINENTAL MOTORS CORPORATION, OF DETROIT, MICHIGAN, A CORPORATION OF VIRGINIA

INTERNAL COMBUSTION ENGINE

Application filed February 16, 1928. Serial No. 254,642.

This invention relates to internal combustion engines and has among its objects the provision of improved means for heating the engine intake mixture. A further feature of 5 my invention resides in a novel construction for controlling the heat applied to the intake manifold, such heat being derived from the exhaust gases of the engine.

One application of the teachings of my invention resides in an engine manifold arrangement wherein the intake and exhaust manifolds are located on opposite sides of the engine, wherein difficulty is experienced in conveniently and efficiently applying the heat 15 of the exhaust gases to the intake mixture.

Further objects and advantages of my invention reside in the novel combination and arrangement of parts more particularly hereinafter described and claimed.

20 In the accompanying drawings illustrating one embodiment of my invention,

Fig. 1 is a plan sectional view through a plurality of the engine cylinders and through the intake and exhaust manifolds,

25 Fig. 2 is a detail sectional view through 2-2 of Fig. 1, and

Fig. 3 is a detail sectional view through 3-3 of Fig. 1.

Referring to the accompanying drawings, 30 reference character 10 represents the cylinder block having a plurality of aligned cylinders 11 here shown as the sleeve valve type wherein each cylinder is provided with intake and exhaust ports 12 and 13 respectively. One 35 or more sleeve valves 14 within each cylinder 11 may be moved in the well known manner for sleeve valves in general causing sleeve intake and exhaust ports 15 and 16 respectively to function with the corresponding cylinder 40 ports. For illustration I have shown my invention applied to a sleeve valve engine of the "Burt-McCollum" type in which a single sleeve valve for each cylinder has a combined reciprocating and oscillating movement. However it should be understood that the particular movement or number of sleeve valves for each cylinder forms no part of my invention in itself. As the description of 45 my invention progresses it will be apparent 50 that my improvements are equally adapted

to any of the well known types of sleeve valve engines or to other types of engines.

Fuel intake mixture is supplied to the cylinders 11 by any suitable intake manifold 17, that illustrated being branched at 18 and 19 55 for respectively supplying intake mixture to the groups of cylinder intake ports 12 which open to the cylinder block intake chambers 20, 21. Longitudinally extending walls 22 between adjacent cylinders divide the intake 60 chambers 20, 21 from cylinder block exhaust chambers 23 which pass the exhaust gases from the cylinder ports 13 to the exhaust manifold 24 having an outlet 25.

The intake manifold 17 is provided with a 65 heater jacket 26 which surrounds or embraces a suitable portion of the intake manifold, exhaust gases from the exhaust manifold 24 being conducted through a tube or cylinder block cored conduit or passage 27 below the intake and exhaust chambers and entering jacket 26 at 28. The exhaust gases after having heated the intake manifold portion embraced by the jacket 26 are preferably returned to the exhaust manifold through 70 jacket outlet 29, return cylinder block conduit 30, and outlet 31 which opens into the exhaust manifold.

In order to positively induce and control the circulation of exhaust gases through the 80 heater jacket 26 I have provided a valve 32 of any suitable construction cooperating with the conduit 27. Thus the valve 27 may be mounted on a rock shaft 33 preferably adjustable manually or automatically by an 85 actuating arm 34. In Figs. 1 and 2 the valve is closed, preventing passage of exhaust gases to the heater jacket, the dotted valve position 32a in Fig. 2 and the full line position in 90 Fig. 3 showing the valve in full open position. In the latter position substantially all of the exhaust gases from the cylinders to the left of the valve 32, as viewed in Fig. 1, will be deflected or guided by the valve into conduit 27 whereby the exhaust gases are 95 forced into the heater jacket 26 and thence through conduit 30 to the exhaust manifold. The exhaust gases from the remaining cylinders will assist in the return flow of gases from jacket 26 by reason of the auto-extrac- 100

tion effect at the opening 31. By locating the valve 32 at varying points along the exhaust manifold 24 or by varying the size of the valve, more or less of the exhaust gases may be diverted from the exhaust manifold and passed to the heater jacket. Furthermore by adjusting the position of valve 32 angularly on its shaft 33 corresponding quantities of the exhaust gases will be bypassed through jacket 26. By adjusting the valve 32 the amount of heating applied to the intake mixture may be conveniently controlled.

What I claim as my invention is:

15. 1. In an internal combustion engine, a cylinder block having a plurality of engine cylinders and a cored passage extending transversely therethrough, intake and exhaust manifolds for the engine respectively located on opposite sides of the engine, a heater jacket for the intake manifold, and means by-passing a portion of the exhaust gases from the exhaust manifold through the said passage in the cylinder block to the heater jacket.
20. 2. In an internal combustion engine, a cylinder block having a plurality of engine cylinders and a passage extending from one side to the other of the block, intake and exhaust manifolds for the engine respectively located on opposite sides of the engine, a heater jacket for the intake manifold, and valve controlled means by-passing a portion of the exhaust gases from the exhaust manifold through the said passage in the cylinder block to the heater jacket.
25. 3. In an internal combustion engine, a cylinder block having a plurality of engine cylinders, intake and exhaust manifolds for the engine respectively located on opposite sides of the engine, a heater jacket for the intake manifold, a conduit transversely through the cylinder block between a pair of adjacent cylinders supplying exhaust gases from the exhaust manifold to the heater jacket, and a second conduit transversely through the cylinder block between another pair of adjacent cylinders returning the exhaust gases from the heater jacket to the exhaust manifold.

40. 4. In an internal combustion engine, a cylinder block having a plurality of engine cylinders, intake and exhaust manifolds for the engine respectively located on the opposite sides of the engine, a heater jacket for the intake manifold, a conduit transversely through the cylinder block between a pair of adjacent cylinders supplying exhaust gases from the exhaust manifold to the heater jacket, a second conduit transversely through the cylinder block between another pair of adjacent cylinders returning the exhaust gases from the heater jacket to the exhaust manifold, and valve controlled means regulating the quantity of exhaust gases by-passed from the exhaust manifold to the heater jacket.

5. In an internal combustion engine, a cylinder block having a plurality of engine cylinders, intake and exhaust manifolds for the engine respectively located on opposite sides of the engine, a heater jacket for the intake manifold, a conduit transversely through the cylinder block between a pair of adjacent cylinders supplying exhaust gases from the exhaust manifold to the heater jacket, a second conduit transversely through the cylinder block between another pair of adjacent cylinders returning the exhaust gases from the heater jacket to the exhaust manifold, and a valve associated with the first said cylinder block conduit controlling the passage of exhaust gases to the heater jacket.

6. In an internal combustion engine, a cylinder block having a plurality of engine cylinders, intake and exhaust manifolds for the engine respectively located on opposite sides of the engine, a heater jacket for the intake manifold, a conduit transversely through the cylinder block between a pair of adjacent cylinders supplying exhaust gases from the exhaust manifold to the heater jacket, a second conduit transversely through the cylinder block between another pair of adjacent cylinders returning the exhaust gases from the heater jacket to the exhaust manifold, and a valve swingingly mounted within the exhaust manifold and associated with one of said cylinder block conduits for controlling the passage of exhaust gases through the heater jacket.

7. In an internal combustion engine, a cylinder block having a plurality of engine cylinders, intake and exhaust manifolds for the engine respectively located on opposite sides of the engine, a heater jacket for the intake manifold, a conduit transversely through the cylinder block between a pair of adjacent cylinders supplying exhaust gases from the exhaust manifold to the heater jacket, and a second conduit transversely through the cylinder block between another pair of adjacent cylinders returning the exhaust gases from the heater jacket to the exhaust manifold, said exhaust manifold having an outlet to one side of the second conduit remote from the first conduit.

8. In an internal combustion engine, a cylinder block having a plurality of engine cylinders, intake and exhaust manifolds for the engine respectively located on opposite sides of the engine, a heater jacket for the intake manifold, a conduit transversely through the cylinder block between a pair of adjacent cylinders supplying exhaust gases from the exhaust manifold to the heater jacket, a second conduit transversely through the cylinder block between another pair of adjacent cylinders returning the exhaust gases from the heater jacket to the exhaust manifold, said exhaust manifold having an outlet to one side of the second conduit remote from the first conduit.

conduit, and a valve within the exhaust manifold associated with the first conduit controlling the passage of exhaust gases to the heater jacket.

5 9. In an internal combustion engine, a cylinder block having a plurality of engine cylinders, intake and exhaust manifolds for the engine respectively located on opposite sides of the engine, a heater jacket for the intake
10 manifold, a conduit between the exhaust manifold and heater jacket, and a valve within the exhaust manifold associated with the conduit for regulating the quantity of exhaust by-passed from the exhaust manifold to the heater jacket.

15 with the intake and exhaust chambers and positioned on opposite sides of the cylinder block, said intake manifold having a heater jacket, a cylinder block conduit below the said chambers between a pair of adjacent cylinders, said conduit communicating with the exhaust manifold and the heater jacket, and a second cylinder block conduit below said chambers between another pair of adjacent cylinders, said second conduit communicating with the exhaust manifold and

10. In an internal combustion engine of the sleeve valve type, a cylinder block having a plurality of cylinders ported for intake and exhaust, intake and exhaust cylinder block chambers respectively communicating with the cylinder intake and exhaust ports, said chambers extending generally transversely of the cylinder block and in opposite directions from the cylinders, intake and exhaust manifolds respectively communicating with the intake and exhaust chambers and positioned on opposite sides of the cylinder block, said intake manifold having a heater jacket, a cylinder block conduit below the said chambers between a pair of adjacent cylinders, said conduit communicating with the exhaust manifold and the heater jacket, and valve controlled means regulating the passage of exhaust gases through said conduit

cooperating with the first conduit to by-pass exhaust gases from the exhaust manifold to the heater jacket and thence back to the exhaust manifold, said exhaust manifold having an outlet to one side of one of said conduits remote from the other of said conduits. 85

13. In an internal combustion engine of the sleeve valve type, a cylinder block having a plurality of cylinders ported for intake and exhaust, intake and exhaust cylinder block chambers respectively communicating with the cylinder intake and exhaust ports, said chambers extending generally transversely of the cylinder block and in opposite directions from the cylinders, intake and exhaust manifolds respectively communicating with the intake and exhaust chambers and positioned on opposite sides of the cylinder block, said intake manifold having a heater jacket, a cylinder block conduit below the said chambers between a pair of adjacent cylinders, said conduit communicating with the exhaust manifold and the heater jacket, and valve controlled means regulating the passage of exhaust gases through said conduit

50 cylinder block conduit said the said chambers between a pair of adjacent cylinders, said conduit communicating with the exhaust manifold and the heater jacket, and a second cylinder block conduit below said chambers between another pair of adjacent cylinders, said second conduit communicat- 115
55 ing with the exhaust manifold and cooperat- ing with the first conduit to by-pass exhaust gases from the exhaust manifold to the heater jacket and thence back to the exhaust mani- 120 fold.

14. In an internal combustion engine of the sleeve valve type, a cylinder block having a plurality of cylinders ported for intake and exhaust, intake and exhaust cylinder block chambers respectively communicating with the cylinder intake and exhaust ports, said chambers extending generally transversely of the cylinder block and in opposite directions from the cylinders, intake and exhaust manifolds respectively communicating with the intake and exhaust chambers and posi-

60 12. In an internal combustion engine of the sleeve valve type, a cylinder block having a plurality of cylinders ported for intake and exhaust, intake and exhaust cylinder block chambers respectively communicating with the cylinder intake and exhaust ports, 165 situated on opposite sides of the cylinder block, 125 said intake manifold having a heater jacket, a cylinder block conduit below the said chambers between a pair of adjacent cylinders, said conduit communicating with the exhaust manifold and the heater jacket, a second cyl- 130

inder block conduit below said chambers between another pair of adjacent cylinders, said second conduit communicating with the exhaust manifold and co-operating with the first conduit to by-pass exhaust gases from the exhaust manifold to the heater jacket and thence back to the exhaust manifold, and a valve within the exhaust manifold associated with one of said conduits for regulating the passage of exhaust gases through the heater jacket.

In witness whereof, I hereunto subscribe my name this 8th day of February, A. D. 1928.
